United States Patent Office

Des. 182,377
Patented Mar. 25, 1958

182,377.

TOY

Anna Edwarda Mosczynski, New York, N. Y.

Application August 16, 1957, Serial No. 47,400

Term of patent 14 years

(Cl. D34—2)

Fig. 1 is a front view of a toy embodying my design;
and

Fig. 2 is a side view thereof.

The characteristic features of the design reside in those features shown in solid line.

I claim:

The ornamental design for a toy, as shown and described.
